J. A. HOLZAPFEL

ANCHOR ROPE PULLEY

Filed Feb. 12, 1923

Patented Jan. 8, 1924.

1,479,813

UNITED STATES PATENT OFFICE.

JOHN A. HOLZAPFEL, OF JACKSON, MICHIGAN.

ANCHOR-ROPE PULLEY.

Application filed February 12, 1923. Serial No. 618,541.

To all whom it may concern:

Be it known that I, JOHN A. HOLZAPFEL, a citizen of the United States, residing at the city and county of Jackson, State of Michigan, have invented certain new and useful Improvements in Anchor-Rope Pulleys, of which the following is a specification.

This invention relates to improvements in anchor rope pulleys.

The main objects of this invention are:

First, to provide an improved combined anchor rope pulley or wringer which may be readily mounted upon or removed from a boat, thus permitting the removal of the anchor rope and anchor if desired.

Second, to provide an improved anchor rope pulley which may, if desired, be locked upon the boat.

Third, to provide an improved anchor rope pulley which provides means for attachment of a painter to the boat.

Further objects, and objects pertaining to details and economies of construction and operation will definitely appear from the detailed description to follow.

I accomplish the objects of my invention by the devices and means described in the following specification. The invention is clearly defined and pointed out in the claims.

A structure which is a preferred embodiment of the invention is clearly illustrated in the accompanying drawing forming a part of this application, in which:

Fig. I is a plan view of my improved anchor rope pulley and wringer.

Fig. II is a view, mainly in vertical central section, on a line corresponding to line 2-2 of Figs. I and III.

Fig. III is a detail vertical transverse section on a line corresponding to line 3-3 of Figs. I and II.

Fig. IV is a plan view of the base member.

Fig. V is a detail section on a line corresponding to line 5-5 of Fig. II.

In the drawing the sectional views are taken looking in the direction of the little arrows at the ends of the section lines and similar numerals of reference refer to similar parts throughout the several views.

Referring to the drawing, I provide a base member 1 adapted to be mounted upon a boat, the base member illustrated being adapted to fit the prow of a boat. This

base member is provided with an upwardly projecting central eye 2 at its forward end and with longitudinal ribs 3, the longitudinal ribs providing a seat for the anchor block designated generally by the numeral 4. The base member is provided with a pair of key-hole shaped sockets 5 and one of its ribs has an upwardly projecting eye 6. The purpose of the sockets and eye will appear as the description proceeds.

The anchor block 4 comprises a pair of side plates 7 spaced to receive the pulleys between them. The pulley block is provided with headed lugs 8 adapted to be engaged with the sockets 5 by a longitudinal movement of the pulley block between the ribs 3.

A latch 9 is pivoted at 10 between the side members of the pulley block and is adapted to engage with the keeper 11 as shown in Fig. III, thereby preventing longitudinal movement of the pulley block in its seat and retaining the lugs 8 in engagement with the sockets 5.

A coiled spring 12 indicated by dotted lines in Fig. II urges the latch to engaging position. The latch is provided with a finger piece 13 which projects through a slot 14 in one of the side plates 7 so that the latch may be disengaged as desired. One of the side plates has a hole 15 which registers with the eye 6 on the base plate so that a padlock may be passed through these holes, thereby locking the pulley block to the plate as desired.

The pulley block has holes 16 in its side members registering with the eye 2 of the base plate so that a painter may be passed therethrough, or, if desired, a lock may be engaged at this point.

The side plates are connected at their upper edges by a cross member 17 having a socket 18 therein adapted to receive the staff of a flag. The wringer pulley 19 is mounted on a fixed journal 20 at the front end 100 of the pulley block. A coacting wringer pulley 21 is carried by the journal 22 movably supported in the elongated bearings 23 in the side plates, these bearings being disposed in a forwardly inclined relation and above the journal of the pulley 19, so that a downward pull on the pulley 21 tends to urge it towards the pulley 19.

A guide pulley 24 is disposed at the rear of and below the plane of the journal 110

of the movable pulley 21, the anchor rope being passed over the pulley 21 and under the guide pulley 24.

With the parts thus arranged a hauling 5 pull on the rope forces the movable pulley 21 toward the pulley 20.

My improved anchor pulley is very convenient to use in that the pulley block may be readily attached to or detached from the 10 base member which may be permanently attached to the boat, or the pulley block may be locked to the base plate, as desired.

I have illustrated and described my improvements in an embodiment which I have found very satisfactory. I have not attempted to illustrate or describe certain 15 modifications or adaptations which I contemplate as I believe the disclosure made will enable those skilled in the art to which 20 my invention relates to embody or adapt the same as may be desired.

Having thus described my invention what I claim as new and desire to secure by Letters Patent is:

1. In a structure of the class described, 25 the combination of a base member adapted for attachment to a boat and having a centrally disposed upwardly projecting eye at its front end and spaced longitudinal ribs 30 providing a pulley block seat and key-hole sockets between said ribs, a pulley block comprising spaced side plates seated between said ribs and having headed lugs engageable with said sockets by a longitudinal 35 movement of the pulley block, said pulley block having an opening therethrough registering with said eye at the front end of said base member, a pivoted spring actuated latch disposed within said pulley block, and 40 a keeper on said base plate coacting with said latch, whereby said lugs are retained in engagement with said sockets, said latch having a laterally projecting finger piece, one of said side plates having an opening 45 therein through which said finger piece projects.

2. In a structure of the class described, 50 the combination of a base member adapted for attachment to a boat and having spaced longitudinal ribs providing a pulley block seat and key-hole sockets between said ribs, a pulley block comprising spaced side plates seated between said ribs and having headed 55 lugs engageable with said sockets by a longitudinal movement of the pulley block, a pivoted spring actuated latch disposed within said pulley block, and a keeper on 60 said base plate coacting with said latch, whereby said lugs are retained in engagement with said sockets.

3. In a structure of the class described, 65 the combination of a base member adapted for attachment to a boat and having spaced longitudinal ribs providing a pulley block seat and key-hole sockets between said ribs,

one of said ribs being provided with an upwardly projecting eye at its rear end, a pulley block comprising spaced side plates seated between said ribs and having headed lugs engageable with said sockets by a longitudinal movement of the pulley block and one of said side plates registering with said eye on said rib, a pivoted spring actuated latch disposed within said pulley block, and a keeper on said base plate coacting with said latch whereby said lugs are retained in engagement with said sockets.

4. In a structure of the class described, the combination of a base member adapted 80 for attachment to a boat and having a centrally disposed upwardly projecting eye at its front end and spaced longitudinal ribs providing a pulley block seat and a socket between said ribs, a pulley block disposed in said seat and having a headed lug engageable with said socket by a longitudinal movement of the pulley block, said pulley block having an opening therethrough 85 registering with said eye at the front end of said base member, a latch on said pulley block, and a keeper on said base plate coacting with said latch, whereby said lug is retained in engagement with said socket.

5. In a structure of the class described, 90 the combination of a base member adapted for attachment to a boat and having spaced longitudinal ribs providing a pulley block seat and a socket between said ribs, a pulley block disposed in said seat and having a headed lug engageable with said socket by a longitudinal movement of the pulley block, 95 a latch on said pulley block, and a keeper on said base plate coacting with said latch, whereby said lug is retained in engagement with said socket.

6. In a structure of the class described, 100 the combination of a base member adapted for attachment to a boat and having spaced longitudinal ribs providing a pulley block seat and a socket between said ribs, one of 105 said ribs being provided with an upwardly projecting eye at its rear end, a pulley block disposed in said seat and having a headed lug engageable with said socket by a longitudinal movement of the pulley block and an opening registering with said eye in said rib, a latch on said pulley block, and a keeper on said base plate coacting with said latch, whereby said lug is retained in engagement 110 with said socket.

7. In a structure of the class described, the combination of a base member adapted for 115 attachment to a boat and having a centrally disposed upwardly projecting eye at its front end and spaced longitudinal ribs providing a pulley block seat and a socket between said ribs, and a pulley block disposed in said seat having a headed lug engageable with said socket by a longitudinal 120 movement of the pulley block.

125

movement of the pulley block, said pulley block having an opening therethrough registering with said eye at the front end of said base member.

- 5 8. In a structure of the class described, the combination of a base member adapted for attachment to a boat and having spaced longitudinal ribs providing a pulley block seat and a socket between said ribs, one of
10 said ribs being provided with an upwardly projecting eye at its rear end, and a pulley block disposed in said seat and having a headed lug engageable with said socket by a longitudinal movement of the pulley block
15 and an opening registering with said eye in said rib.

9. In a structure of the class described, the combination of a base member adapted for attachment to a boat and having a centrally disposed upwardly projecting eye at its front, a pulley block having headed lugs, said base member having sockets with which said lugs are engageable by a longitudinal movement of the pulley block, said pulley
25 block having an opening therethrough registering with said eye at the front end of said base member, a latch on said pulley block, and a keeper on said base plate coacting with said latch, whereby said lugs are
30 retained in engagement with said sockets.

10. In a structure of the class described, the combination of a pulley block comprising spaced side members, a pulley journaled between said side members, and a connecting
35 cross member for said side members disposed at the upper edge thereof, said cross member having a flag-staff socket integral therewith.

11. In a structure of the class described, the combination of a pulley block comprising a pair of spaced side members, a fixed wringer pulley journaled between said side members, a coacting movable wringer pulley

provided with a journal, said side plates being provided with elongated forwardly inclined bearings for said journal disposed at the rear of and in a plane above the axis of the fixed wringer pulley, and a guide pulley disposed at the rear of and below the plane of the axis of the movable pulley. 45
50

12. In a device of the class described, the combination of a pulley block comprising a pair of spaced side members, a pair of coacting wringer pulleys, one of which is disposed with its journal above and at the rear of the journal of the other, said side members having forwardly inclined elongated bearings for the journal of the rear pulley so that such pulley is supported to be moved downwardly and forwardly towards the 60 front wringer pulley, and a guide pulley disposed at the rear of and with its axis below the plane of the rear wringer pulley. 55

13. In a device of the class described, the combination of a pulley block comprising a wringer pulley having a fixed journal and a movable coacting wringer pulley, said pulley block having elongated forwardly inclined bearings for the journal of the movable pulley, the axis of which when in its lowest position is above the plane of the fixed pulley journal, and a guide pulley disposed at the rear of and below the said movable wringer pulley. 65
70

14. In a device of the class described, the combination of a pulley block, a pair of coacting wringer pulleys, said pulley block having elongated bearings in which the journal of one of said pulleys is supported so that such pulley may move toward and from its coacting pulley, and a guide pulley disposed at the rear of and below said movable pulley. 75
80

In witness whereof I have hereunto set my hand and seal.

JOHN A. HOLZAPFEL. [L. s.]
